COMPUTER CONSOLE

Clarence F. Graser, Poughkeepsie, and William S. Shepley, Jr., Rhinebeck, N.Y., assignors to International Business Machines Corporation, New York, N.Y., a corporation of New York

Filed July 28, 1964, Ser. No. 81,048

Term of patent 14 years

(Cl. D26—5)

FIG. 1

Des. 200,469

PAGE 2

FIG. 2

FIG. 3

FIG. 1 is a front perspective view of a computer console showing our design.

FIG. 2 is a view in perspective of the rear and right-hand side of the console in FIG. 1.

FIG. 3 is a left side elevation of the console.

We claim:

The ornamental design for a computer console, substantially as shown.
